UNITED STATES PATENT OFFICE.

THOMAS M. McWHORTER, OF BIG SPRING, TEXAS.

EARTH-AUGER.

No. 843,764.

Specification of Letters Patent.

Patented Feb. 12, 1907.

Application filed July 9, 1906. Serial No. 325,366.

To all whom it may concern:

Be it known that I, THOMAS M. McWHORTER, a citizen of the United States, residing at Big Spring, in the county of Howard and State of Texas, have invented 5 certain new and useful Improvements in Earth-Augers, of which the following is a specification.

My invention pertains to improvements in 10 earth-augers.

It has for its object to increase or facilitate the action of the auger in agitating or loosening the bored earth for its effective removal and for preventing the choking of the auger, 15 and to accomplish these ends in a simple, inexpensive, and ready manner.

Said invention consists of certain structural features substantially as hereinafter fully disclosed, and specifically pointed out 20 by the claims.

In the accompanying drawings, illustrating the preferred embodiment of my invention, Figure 1 is an elevational view thereof. Fig. 2 is a cross-section viewing downward. 25 Fig. 3 is a like section oppositely viewed, and Fig. 4 is a longitudinal section of the same.

In the disclosure of my invention I employ what is known as the ordinary "earth-socket" or tubular form of auger 1, having 30 the usual longitudinal lateral opening 2, with its edges suitably tapered or beveled for aiding the removal of the earth in the boring operation, the bottom edge of said auger being beveled or sharpened, as at 3, and acting in 35 the capacity of a bit for cutting or boring the earth.

A stout pin 4 is arranged to extend transversely through the tube or auger 1 contiguous to the cutting or bit end thereof, and 40 fixed thereto by suitably passing it through apertures in the sides of said tube or auger and hammering down the ends of said pin from the outside upon the tube or auger.

In the use of the device the tube or auger during the boring operation is kept well supplied with water by pouring the same from above thereinto, whereby said pin will produce a churning action upon the loosened earth, which latter will rise and be carried upward with the water and be delivered or 45 discharged therefrom in the usual way, and the interior of the auger thus be effectively prevented from becoming choked or clogged, as would otherwise be the case and as has been found by practical experience to take 50 place in the use of this general style of auger. In actual operation, with the use of this transverse pin the auger has been found to work perfectly free from choking or clogging and to provide for doing its work satisfactorily. 55 Said tool is adapted by the use of any well-known form of coupling to be connected or coupled to the plunger-rod (not shown) commonly employed in connection therewith for aiding in actuating it. 60

I claim—

A device of the character described, comprising an "earth-socket," forming the auger proper, having a longitudinal lateral opening, with effective earth-removing edges, said 70 "earth-socket" having its bottom edge adapted to form a bit and having arranged centrally therein, just above the plane of said beveled bottom edge a plain unequipped cross-pin. 75

In testimony whereof I have signed my name to this specification in the presence of two subscribing witnesses.

THOMAS M. McWHORTER.
